UNITED STATES PATENT OFFICE.

RAYMOND V. DAVIS, OF DENVER, COLORADO.

HEEL-PROTECTOR.

1,274,692.

Specification of Letters Patent. Patented Aug: 6, 1918.

Application filed September 18, 1917. Serial No. 191,972.

To all whom it may concern:

Be it known that I, RAYMOND V. DAVIS, a citizen of the United States, residing at Denver, in the county of Denver and State 5 of Colorado, have invented certain new and useful Improvements in Heel-Protectors, of which the following is a specification.

This invention relates to certain new and useful improvements in heel protectors and 10 is especially designed for the protection of the heels of ladies' shoes against scratching and disfiguring resulting from the driving and operating of automobiles.

It is well known that in the operation of 15 foot pedals of motor vehicles the heel is given a purchase or is rested on the floor of the vehicle with the toe portion of the foot bearing on the face of the pedal. During the depression and release of the pedal 20 the foot usually rubs more or less over the floor at the heel and causes scratching thereof. Further, the foot might accidentally leave the pedal and the consequences are readily apparent.

25 The principal object of my invention, therefore, is to provide a protector which will fully protect the heel without hindering the movement of the foot, and at the same time be easily applied and removed 30 from the heel.

The invention further resides in the features of construction hereinafter specifically described and succinctly claimed, reference being had to the accompanying drawing 35 wherein—

Figure 1 is a side elevation of the improved heel protector applied to a shoe, the latter being shown as resting on a foot pedal of a motor vehicle; and

40 Fig. 2 is a rear elevation of the protector.

Referring more in detail to the accompanying drawing, the numeral 1 designates a U-shaped leaf spring which has its extremities riveted or otherwise secured to the forward edge portions of the heel protector sections 2 so that their rear or inner edge portions will be free of the spring to conform to the shape and contour of the heel. The protector sections are thus yieldingly 45 and resiliently connected to expand and flex 50

for conformably fitting varying sizes and shapes of heels.

Each heel protector section is bulged at its upper portion in more or less of a semi-globular contour while the lower portion is 55 extended downwardly in an attenuated form and projects slightly below the resilient connector 1 so as to protect the latter from wear on the ground and also against distortion.

When the protector is off the shoe, or is 60 inoperative, the spring normally holds the upper ends of the sections spaced, as depicted in Fig. 2, but when the spring clip is spread apart to embrace the heel, said 65 upper ends are brought together to thereby entirely cover and protect the heel from the back.

The material from which the protector is 70 formed may be any thin metal like, for instance, rolled aluminum which may be painted or otherwise decorated to suit the tastes of the purchasing public. Further, instead of metal, fiber or hard leather will 75 answer the purpose.

The heel may be rolled around, when supplied with this protector, without being 80 scratched or marred. Although the invention has here been described in detail, it is understood that such changes in design and structure may be resorted to in the manufacture of the protector as the scope of the appended claims may permit.

What is claimed is:—

1. A heel protector comprising a protector 85 body formed of a plurality of separable sections shaped to fit the heel, and a flat leaf spring bent into substantially U-form and secured at its ends to the sections for holding them about the heel.

2. A heel protector comprising a protector 90 body formed of a plurality of separable sections shaped to fit the heel, and resilient means embracing the lower ends of the sections and secured thereto at the outer edges 95 thereof whereby the upper ends of the sections may yield apart.

3. A heel protector comprising a body 100 formed with a bowl divided vertically into sections for conformably receiving the heel

of a shoe, and resilient means connecting the bowl sections adjacent the lower ends for frictionally clamping the same about the outer face of the heel.

- 5 4. A heel protector comprising a body formed of a pair of side sections for extending over the side and back of the heel

of a shoe, and a spring encircling the sections and secured to the same at its extremities to permit free movement of the sections 10 at their meeting edges.

In testimony whereof I affix my signature.

RAYMOND V. DAVIS.
